FLUID STIRRING DEVICE

Marshall Silver, Huntington Woods, Mich.

Application January 2, 1952, Serial No. 264,549

5 Claims. (Cl. 259—107)

1

This invention relates to fluid stirring devices adapted for use upon a cylindrical container, and more particularly to a stirring device for mixing and stirring paint.

It is the object of the present invention to provide a stirring device which may be removably positioned upon the open end of a fluid container, such as a paint can, and which includes a manually rotatable paddle positionable down into the fluid within the container for stirring the same.

It is the further object of this invention to provide a simplified fluid stirring device which is adapted for use upon containers of different diameters.

It is the object of the present invention to provide a paint stirring device which eliminates the use of a stick for such purpose, keeps the user's hands clean, and is fully effective as a stirring mechanism.

It is the further object of this invention to provide a simplified and inexpensive paint stirring device which is easy to assemble and which is easy to mount upon the open end of a paint or other fluid container.

These and other objects will be seen from the following specification and claims in conjunction with the appended drawing in which:

Fig. 1 is a plan view of the present stirring device mounted upon a fluid container.

Fig. 2 is a section taken on line 2—2 of Fig. 1.

Fig. 3 is a section on an enlarged scale taken on line 3—3 of Fig. 2.

Fig. 4 is an elevational view partially in section showing the paddle shaft and handle construction in one piece; and

Fig. 5 is a fragmentary elevational section showing a slightly different form of bearing mounting.

It will be understood that the above drawing illustrates merely a preferred embodiment of the invention and that other embodiments are contemplated within the scope of the claims hereinafter set out.

Referring to the drawing, a fluid container 11, which may contain paint, has bottom wall 12, and is provided at its upper open end with an annular formed flange 13 with an inner bearing 14. Said flange is adapted to removably receive the conventional cover whose depending flange cooperates with flange 13.

The present invention contemplates a stirring mechanism adapted for use upon container 11, which may be a gallon container, for illustration.

The stirring device includes a substantially semi-circular formed plate 15 which has a cen-

2

tral circularly shaped platform 16 and a pair of horizontally extending annularly shaped flanges 17 and 19.

Platform 16 terminates in the upright shoulder 18 which is substantially circular in shape, and the upper end of shoulder 18 terminates in the horizontally arranged flange 17.

Flange 17 terminates in the upright peripheral flange 20, which is substantially circular in shape; and the upper end of shoulder 20 terminates in the peripheral horizontally arranged flange 19, which as shown in Fig. 2 extends laterally of the side walls of container 11.

An upright bearing is mounted upon the platform 16 and consists of the uprights 21 with right angular legs 22 at their lower ends suitably secured to a platform 16, such as by the welds 23. The upper ends of uprights 21 are interconnected by the horizontal portion 21' which has a centrally depressed apertured portion 25 in registry with an upwardly formed apertured portion 24 formed within platform 16.

Thus, the upright bearing 21—21'—22 is secured to the plate 16 and its aperture is in registry with the corresponding aperture formed in plate 15.

Upright manually rotatable shaft 26 is journaled through the registering apertures in bearing 21 and platform 16, and extends downwardly into container 11.

The upper end of shaft 26 has a reduced threaded portion 27 upon which the handle 28 is threadably secured at one end.

Horizontally arranged handle 28 has an upright operating element 29 swivelly secured as at 30 to the outer end of handle 28.

The upright, preferably rectangular paddle 31 has a curved upright edge 32 which engages around the lower portion of shaft 26 and is suitably secured therewith as by the welds 33, shown in Fig. 3. The stirring device may be used with the upright paddle 31 alone for certain sizes of containers; however Figs. 2 and 3 show an upright, preferably rectangular paddle blade 34 which is hinged at one upright edge to the adjacent upright edge of paddle 31.

The hinge employed is so constructed that blade 34 may lie in parallel engaging relation with paddle 31, as shown in dotted lines in Fig. 2, or may be fully opened into substantial coplanar or parallel relationship with paddle 31.

The particular hinge employed, generally designated at 35, includes a circularly curved tongue 36 which is formed from paddle 31 and extends loosely through an upright slot 37 formed in pad-

dle blade 34. However, paddle 31 has extensions 39 which are substantially parallel to paddle 31 and which are adapted to limit the opening movement of plate 34 to the position shown in Fig. 3.

Thus, by rotating shaft 26 in a clockwise direction within container 11, blade 34 will open into substantially coplanar relationship shown in Figs. 2 and 3, the outer upright edge of blade 34 being forwardly curved as at 38.

The lower horizontal edges of paddle 31 and blade 34 are serrated as at 40 and are adapted for scraping over the bottom wall 12 of container 11. It is apparent that counter-clockwise rotation of shaft 26 would cause a partial pivotal movement of blade 34 and, therefore, would not be fully effective for mixing the paint or other fluid.

The above described stirring device may also be selectively used for a smaller diameter container, such as the quart size container 41-42 shown in dotted lines in Fig. 2. The second container 41 shown in dotted lines is similarly provided with a conventional internal annular flange 43 and corresponding bead 44 at its open end.

The above described plate 15 is provided with the two spaced upright shoulders 18 and 20 to thereby permit the selective use of the one stirring device with either a large or a small container.

In the preferred embodiment, Fig. 2, the shoulder 20 cooperates with the bead 14 on flange 13 and the adjacent horizontal flange 19 of plate 15 bears upon container flange 13. In some situations the shoulder 20 will snugly engage the bead 14, however, as these containers are not standard exactly, there will be situations where the shoulder 20 will be more loosely positioned within and adjacent the bead 14.

In the event that the stirring device is to be used for a substantially smaller container, such as the quart container 41-42, then the upright shoulder 18 is adapted for positioning within and cooperation with bead 44 of the horizontal container flange 43 shown in dotted lines. Of course, it will be noted that the paddle 31 will then be elevated to the dotted line position shown, and the blade 34 will be folded over paddle 31. Of course, the shaft 26 would be moved upwardly sufficiently so that paddle 31 will bear against the bottom 42 of container 41.

Horizontally arranged pin or shaft 45 is secured at one end to handle 28 adjacent shaft 26 and provides a means whereby a paint brush may be suspended therefrom and hang down into the container. For this purpose, a small loop of cord is tied around the paint brush handle and a portion of the loop is slipped over the free end of the pin 45.

The present stirring device includes the semi-circular plate 15 whereby during the painting operation the same is not removed from the container as the space provided is sufficient for dipping of the paint brush. The straight edge 10 of plate 15 provides a brush wiping edge for removing excess paint.

In operation the user holds the plate 15 in place with one hand and rotates the handle 28 with his other hand.

It is contemplated that the present mixing device might also be constructed of such dimension as to be selectively used with a pint or quart container. In that case, it is contemplated that the blade 34 may be eliminated, if desired.

Referring to Fig. 4, the upright shaft 46 carry-

ing paddle 47 projects upwardly through the aperture in platform 16 and through the corresponding aligned aperture in bearing 21, and the upper portion of shaft 46 is bent normally of the body of the shaft defining the handle arm 48 which is upturned at its outer end as at 49 to provide a grip for the handle. This provides a more simplified structure wherein the handle is formed as a part of the shaft.

The bearing 21-22 shows one form of journal for shaft 26, however, it is contemplated that other types of bearing may be employed, such as shown for illustration in Fig. 5. In this figure there is shown the central platform 50 corresponding to platform 16 and fragmentarily the adjacent horizontally arranged flange 52 which corresponds to flange 17 in Fig. 2. The platform 50 is upturned as at 51 defining a sleeve within which is pressed and secured the cylindrical bearing or bushing 53 which journals manually rotative shaft 54.

Having described my invention, reference should now be had to the claims which follow for determining the scope thereof.

I claim:

1. A paint stirring device adapted for use upon a cylindrical paint container comprising a centrally apertured substantially semi-circular plate positionable over the open end of said container, an upright bearing secured to said plate in registry with the aperture therein, a manually rotative upright shaft journaled through said bearing and plate and adapted to be projected down into said container, a substantially flat rectangularly shaped upright paddle secured at one upright edge to the lower end of said shaft, with its other upright edge adapted to be extended toward and in proximity to the interior surface of said container, and an upright paddle blade hinged at one upright edge to the other upright edge of said paddle and adapted for positioning in coplanar registry therewith.

2. A fluid stirring device adapted for use upon a cylindrical container comprising a centrally apertured substantially semi-circular plate positionable over the open end of said container, an upright bearing secured to said plate in registry with the aperture therein, a manually rotative upright shaft journaled through said bearing and plate and adapted to be projected down into said container, a substantially flat rectangularly shaped upright paddle secured at one upright edge to the lower end of said shaft, with its other upright edge adapted to be extended toward and in proximity to the interior surface of said container, and an upright paddle blade hinged at one upright edge to the other upright edge of said paddle and adapted for positioning in coplanar registry therewith, the bottom horizontal edge of said paddle blade being serrated.

3. A fluid stirring device adapted for use upon a cylindrical container comprising a centrally apertured substantially semi-circular plate positionable over the open end of said container, an upright bearing secured to said plate in registry with the aperture therein, a manually rotative upright shaft journaled through said bearing and plate and adapted to be projected down into said container, a substantially flat rectangularly shaped upright paddle secured at one upright edge to the lower end of said shaft, with its other upright edge adapted to be extended toward and in proximity to the interior surface of said container, and an upright paddle blade

hinged at one upright edge to the other upright edge of said paddle and adapted for positioning in coplanar registry therewith, said hinge including a curved tongue on said paddle loosely extending through a slot in said blade and with said paddle having an extension in substantial alignment therewith to limit the opening pivotal movement of said blade into coplanar relation with said paddle.

4. A fluid stirring device adapted for use upon a cylindrical container comprising a centrally apertured substantially semi-circular plate positionable over the open end of said container, an upright bearing secured to said plate in registry with the aperture therein, a manually rotative upright shaft journalled through said bearing and plate and adapted to be projected down into said container, and a substantially flat rectangularly shaped upright paddle secured at one upright edge to the lower end of said shaft, with its other upright edge adapted to be extended toward and in proximity to the interior surface of said container, said circular plate having a straight line edge on one side adapted to cooperate with the adjacent rim of said container permitting access of a paint brush to the interior of said container without removal of said plate, said edge also acting as a brush wiper, said plate having an annular upright shoulder adjacent its periphery adapted to cooperate with the interior wall of said container, said shoulder terminating at its upper end in a horizontally extending outwardly directed peripheral flange which rests upon the upper open end of said container and extends laterally outward thereof, said plate having a second annular upright shoulder spaced inwardly of said first shoulder cooperable with the interior wall of a second container of less dimension than said first container, said second shoulder terminating at its upper end in a second horizontally outwardly directed flange adapted to rest upon the upper open end of said second container.

5. A fluid stirring device comprising a cylindrical container comprising a centrally apertured substantially semi-circular plate positioned over the open end of said container, an upright bearing secured to said plate in registry with the

aperture therein, a manually rotative upright shaft journalled through said bearing and plate and projecting down into said container, and a substantially flat rectangularly shaped upright paddle secured at one upright edge to the lower end of said shaft, with its other upright edge extended toward and in proximity to the interior surface of said container, said circular plate having a straight line edge on one side cooperating with the adjacent rim of said container permitting access of a paint brush to the interior of said container without removal of said plate, said edge also acting as a brush wiper, said container having an annular beaded internal flange at its open end, said plate having an annular upright shoulder adjacent its periphery cooperable with the interior edge of said flange, said shoulder terminating at its upper end in a horizontally extending peripheral flange which rests upon said beaded flange and extends laterally outward of said container, said plate having a second annular upright shoulder spaced inwardly of said first shoulder cooperable with the edge of an interior beaded flange of a second container of less dimension than said first container, said second shoulder terminating at its upper end in a second horizontally extending outwardly directed flange adapted to rest upon the upper open end of said second container.
